[57] CLAIM

The ornamental design for a preprogrammed toy sound generator, substantially as shown and described.

DESCRIPTION

FIG. 1 is a front perspective view showing our design of the preprogrammed toy sound generator;

FIG. 2 is a front elevational view of the preprogrammed toy sound generator;

FIG. 3 is a rear elevational view of the preprogrammed toy sound generator;

FIG. 4 is a right-side elevational view of the preprogrammed toy sound generator;

FIG. 5 is a left-side elevational view of the preprogrammed toy sound generator; and

FIG. 6 is a top plan view of the preprogrammed toy sound generator.

FIG. 1.

FIG. 2.

FIG. 3.

FIG. 4.

FIG. 5.

FIG. 6.
